UNITED STATES PATENT OFFICE

ALBERT G. HAMILTON, OF PITTSBURGH, PENNSYLVANIA, ASSIGNOR TO J. T. & A. HAMILTON COMPANY, OF PITTSBURGH, PENNSYLVANIA, A CORPORATION OF PENNSYLVANIA

DESIGN FOR A GLASS CONTAINER

Application filed May 14, 1932. Serial No. 43,800. Term of patent 7 years.

To all whom it may concern:

Be it known that I, ALBERT G. HAMILTON, a citizen of the United States, residing at Pittsburgh, county of Allegheny, and State of Pennsylvania, have invented a new, original, and ornamental Design for Glass Containers, of which the following is a specification, reference being had to the accompanying drawing, forming a part thereof, and in

which the figure is a perspective view illustrating a glass container embodying my new design.

I claim:

The ornamental design for a glass container, substantially as shown.

In witness whereof, I have hereunto set my hand.

ALBERT G. HAMILTON.
